[57]

ABSTRACT

A single piece unitary housing for an electric light bulb having a flexible, biasing portion positioned on the front face of the housing. The biasing portion has elongated members, extending longitudinally outward in opposite directions from the face of the housing, to firmly hold the housing against a support member.

FLUSH MOUNT INDICATOR HOUSING

BACKGROUND OF THE INVENTION

The present invention relates to a switchboard or panel type visual indicator and particularly to a flush mount indicator assembly.

Light indicators for mounting on appliance panels, instrument panels, switchboards and the like are frequently positioned in close quarters and must occupy a minimum of space. Further, these indicators must be installed in these close quarters with a minimum of effort.

Typical prior art indicators are illustrated in U.S. Pat. No. 2,221,078 (Dotterer) and U.S. Pat. No. 3,329,951 (Ryan). These indicators are not entirely suited for all applications. The Dotterer indicator light and assembly is not positioned closely against the instrument panel and, as a consequence, does not readily fit in, or is not readily installed in the crowded quarters of a typical instrument panel. Further, the bracket which engages the light and the instrument panel is rigid and will not accommodate slight misalignments between the light, indicator button and panel opening. In addition, the Dotterer indicator assembly is manufactured from a plurality of components and cannot be rapidly mass produced in an economical manner.

The Ryan indicator is a unitary assembly containing integral, flexible side wings to hold the assembly firmly against an instrument panel. These side wings, however, have a propensity to break off when the indicator is being mounted on a panel since they can bend more than 90° backwards during installation. Further, this reference requires a rib portion on the lower part of the assembly to act as a stabilizer which increases the cost of the assembly.

SUMMARY OF THE INVENTION

It is an object of this invention to provide a readily manufactured, single piece, unitary housing for an electric light bulb which can be positioned in close proximity to an instrument panel and occupy a minimum of space.

It is another object of this invention to provide a single piece, unitary housing for an electric light bulb having a flexible biasing means positioned on the face of the housing to aid in mounting the housing on an instrument panel.

It is a specific object of this invention to provide a single piece, unitary housing for an electric light bulb having a flexible biasing means positioned on the face of the housing which eliminates the need for stabilizing ribs on the housing.

In an embodiment, therefore, the present invention relates to a housing for an electric light bulb comprising in integral combination, a bulb retaining portion and a lead retaining portion extending from said bulb retaining portion. The bulb retaining portion has a front face portion having a keyhole slot therein opening away from the lead retaining portions of the housing. An integral, flexible, biasing portion positioned below the slot extends outward from the face portion of the bulb retaining portion and comprises a pair of spaced-apart, outwardly extending fingers extending in the direction of the keyhole opening and spaced on either side of the keyhole and an outwardly extending tab portion extending in the direction of the lead retaining portion. This housing can be readily positioned in close proxim-

ity to an instrument panel and does not require stabilizing ribs on the face of the housing to hold the housing in a firm position. Further, the flexible, biasing portion is not subject to breakage.

In a more limited embodiment, the plane of the face of the lead portion is spaced behind the plane of the face of the bulb retaining portion thereby spacing the lead portion away from the instrument panel when installed thereon.

Other objects, embodiments, and a more detailed description of the present invention will be found in the discussions relating to the drawings illustrating the single piece, unitary housing.

BRIEF DESCRIPTION OF THE DRAWINGS

FIG. 1 is a front, elevational view of the light housing.

FIG. 2 is a side elevational view of the housing.

FIG. 3 is a side elevational view of the housing illustrating the relationship of the housing and an instrument panel when mounted thereon.

FIG. 4 is a top, plan view of the housing.

FIG. 5 is a top, plan view of the housing showing the housing mounted on the instrument panel.

FIG. 6 is a top, section view of the housing when mounted on an instrument panel taken along section line 6-6 of FIG. 3.

FIG. 7 is a top, plan view of the lens fastener which interconnects the housing and the instrument panel.

FIG. 8 is a front, elevational view of the electric light bulb, resistor and leads which are contained within the housing.

DETAILED DESCRIPTION OF THE INVENTION

Referring to the figures there is shown a flush mount indicator housing 1 which is of a single piece, unitary construction formed from a suitable, flexible, insulating material well known to those trained in the art such as nylon.

Referring to FIGS. 1-3, light housing 1 comprises a bulb retaining portion 2 and a lead retaining portion 7 positioned below the retaining portion 2. Lead openings 11 are positioned on the bottom of lead retaining portions 7 to receive the electrical leads 20 that lead to light 17 when positioned in the housing.

Bulb retaining section 2 has a front face 3, a back surface 4 and side walls 5. Keyhole slot 6, comprising a tapered top opening 6a and a circular bottom opening 6b, is positioned on the front face 3 of bulb retaining section 2. It is to be noted that circular opening 6b has a diameter greater than the width of the bottom of tapered opening 6a. This difference forms a shoulder between opening 6a and 6b which will engage lens fastener 12 and mount the housing on instrument panel 23 via opening 24.

Referring to FIG. 7, lens fastener 12 comprises a shank portion 13, an optical portion 14 and shoulder extensions 15 and 16. This lens fastener is of a type well known to those trained in the art as illustrated in U.S. Pat. No. 3,329,951.

An integral, flexible, biasing portion 8 is positioned on the front face 3 of bulb retaining section 2. Biasing portion 8 comprises a pair of spaced apart, upper tabs 10 which are spaced on either side of keyhole slot 6 to allow passage of lens fastener 12 therethrough. Lower tab 9, also part of biasing portion 8, extends downward and outward in the direction of lead retaining portion

7, and like tabs 10 extends longitudinally outward from the face of housing 1.

Referring to FIGS. 3 and 8, light 17 is positioned in the interior of housing 1 to activate optical portion 14 of lens fastener 12 and comprises leads 18, resistor 19 and insulated leads 20 which extends out of lead opening 11. Insulated leads 20 and leads 18 are firmly interconnected by clamps 21 on insulated leads 20. Pinch indentations 26 (FIGS. 1 and 3) provide a firm interconnection between housing 1 and insulated leads 20 and permanently affix light 17 within the housing. Interior wall 25 is positioned in the interior of lead retaining portion 7 and separates leads 18 when light 17 is positioned within the housing. The interior of back wall 4 in a bulb retaining section 2 is fluted to form reflector surface 22 to reflect the light emitted by light 17 outwards through keyhole slot 6 and activate lens member 12.

Referring to FIGS. 3 and 6, light housing 1 is mounted on instrument panel 23 by first inserting lens member 12 in circular opening 24 in panel 23. Shank extension 15 is of the same diameter as opening 24. When light 12 is inserted in opening 24, optical portion 14 of light 12 also serves to engage the perimeter of opening 24. Housing 1 is then affixed to lens connecting member 12 by placing biasing portion 8 against wall 25 and pushing the biasing portion of the housing inwards. This causes upper tabs 10 and lower tab 9 to flex inward and allows keyhole slot 6 to engage shank 13 and base extension 16 of lens member 12. Base extension 16 is positioned on the interior of bulb retaining section 2 and shank 13 passes down through the narrow opening in opening 6a and is engaged and retained within circular opening 6b of keyhole slot 6 by base extension 16. Biasing portion 8 presses against instrument panel 23 and provides a very firm interconnection between light housing 1 and the panel. It is to be noted that upper tab 10 can be pushed only as far back as face 3 of bulb retaining section 2. Similarly, lower tab 9 can be only pushed back to the front portion of lead retaining portion 7. As a consequence, these respective portions of biasing portion 8 are not subject to snapping or

breaking off when housing 1 is attached to an instrument panel by lens connecting member 12. Further, biasing portion 8 provides such a firm interconnection between the housing and the instrument panel so that no stabilizing ribs are needed on the front of lead retaining portion 7 to stabilize the light housing.

In a typical commercial embodiment, the housing 1 of the present invention has a maximum width of 0.510 inches versus a maximum width of 0.830-1.080 inches 10 for the commercial embodiment of the Ryan housing illustrated in U.S. Pat. No. 3,329,951. Further, the housing of the present invention, when installed has a thickness much less than the Ryan housing. Thus the housing of the present invention is more readily positioned in tight quarters than prior art devices.

We claim as our invention:

1. A housing for an electric light bulb comprising in integral combination:

- a. a bulb retaining portion,
- b. an integral lead retaining portion extending from said bulb retaining portion,
- c. said bulb retaining portion having a front face portion, a pair of side walls and a back portion,
- d. said front face portion of the bulb retaining portion having a keyhole slot therein opening in a direction away from said lead retaining portion; and,
- e. an integral, flexible, biasing portion extending outward from said face portion positioned opposite from the opening of the keyhole slot,
- f. said biasing portion having a pair of spaced-apart, outwardly extending fingers extending in the direction of the keyhole opening and spaced on either side of the keyhole and an outwardly extending tab portion extending in the direction of the lead portion.

2. A housing according to claim 1 wherein an electric light bulb is positioned in said bulb retaining portion adjacent to the key hole slot.

3. A housing according to claim 1 wherein the plane 40 of the face of the lead portion is spaced behind the plane of the face of the bulb retaining portion.
